ROLL DOFFING TRUCK

William H. Dean, Jr., Greenville, S. C., assignor to Deering Milliken Research Corporation, Pendleton, S. C., a corporation of Delaware

Application May 28, 1954, Serial No. 433,105

5 Claims. (Cl. 214—350)

This invention relates to trucks and more particularly to the invention relates to trucks suitable for use in doffing a roll of material from a loom.

Substantially all looms in use at the present time provide a driven roll for the collection of material being woven and such an arrangement necessitates frequent removal of the full rolls of material. The rolls on which the woven material is collected are generally provided with a recess in either end and are secured in position by a pair of pins which are a part of the loom proper and which are adapted to enter the recesses in the roll ends. In order that the roll may be removed when necessary, one of the pins is resiliently mounted and adapted for movement along the longitudinal axis of the roll. To remove the roll of woven material it is necessary that the roll be moved lengthwise relative to the loom frame in the direction of the resiliently mounted pin until the other pin is free of the roll. The end of the roll remote from the resiliently mounted pin can then be moved outwardly from the loom a sufficient distance to allow the roll to be moved lengthwise in the opposite direction to clear the roll of the resiliently mounted pin.

Because of the relatively involved manipulations required for the removal of a full roll of woven material from a loom, there has not heretofore been available a suitable mechanical apparatus for use in performing this operation and at present the rolls are removed in almost all instances entirely by hand. Further, since the roll is only slightly longer than the width of the woven material when the loom is weaving at full width, the heads of the roll are so narrow that they do not furnish suitable handles and it is necessary that the roll of material be removed by actual contact of the loom doffer's hands with the woven material on the roll. Such a procedure is always undesirable since it is substantially impossible for the loom doffer to maintain clean hands at all times and the woven material is frequently soiled during its removal. With glass fabrics such a procedure is undesirable for the additional reason that the pressure of the roll of woven material against the worker's hands completely distorts the weave of the fabric and it has heretofore generally been necessary to weave at less than full width in order that there would be provided on the roll of woven material heads of sufficient length to serve as handles for the removal of the roll from the looms. A still further disadvantage of the conventional procedure for doffing rolls of woven material from a loom is that at present even moderately heavy rolls of material require two men for doffing and even with a plurality of men cooperating together to doff a single loom, the weight of material that can be placed upon the roll before doffing is limited.

It is an object of the present invention to provide a truck adapted for use in the doffing of a full roll of woven material from a loom.

It is a further object of the invention to provide a truck capable of doffing a full roll of woven material without

2

physical contact of the truck or of the operator thereof with the woven material on the roll.

It is a still further object of the invention to provide a truck capable of doffing even very heavy rolls of woven material from a loom without undue physical strain upon the operator.

The above as well as other objects of the invention are accomplished by the provision of a truck comprising a wheeled frame preferably of rectangular construction with a rotatable shaft running lengthwise of the frame. A pair of upstanding arms are carried by the rotatable shaft and are movable with respect to the frame from a position such that the upper extremities of the arms are approximately centered with respect to the width of the frame to a position such that the upper extremities of the arms lie in a plane to one side of the frame. The upper extremities of the two arms are provided with means to support a roll of woven material and at least one of the arms and preferably both of the arms are also provided with means adapted to contact the end faces of the heads of the roll so that the roll can be moved lengthwise for removal from the loom. The truck is also provided with means adapted to move the upstanding arms when supporting a roll of woven material from a position such that their upper extremities are to one side of the frame to a position such that their upper extremities are approximately centered with respect to the width of the frame.

Many features and advantages of the new truck will be readily apparent from the above description. The truck is extremely simple in design and operation yet it makes the doffing of even very heavy rolls a one man task. A further advantage of the new truck is that it can readily be constructed to be of such narrow width that it may be passed between the narrowest of loom alleys without difficulty even when carrying a full roll of material. A still further advantage of the new truck is that it makes possible the removal of a roll of material woven to full loom width without the woven material being contacted, thereby eliminating any possibility of the material becoming soiled or of the weave of the material becoming distorted.

A preferred embodiment of the invention will now be described in detail with reference to the accompanying drawings in which:

Figure 1 is a view in perspective showing the truck in load receiving position; and

Figure 2 is a view in perspective of a portion of the truck showing the parts in load carrying position.

Referring to the drawings in greater detail, there is indicated by the reference numeral 10 a long narrow frame made of angle iron or like material. The frame should be of sufficient length to accommodate a roll of material from the particular type of loom with which the truck is to be employed and should be of such narrow width as to readily enter a loom alley between two rows of looms. The frame 10 is provided with a handle 11 and wheels or casters 12 so that it may readily be moved in any desired direction.

Extending lengthwise of frame 10 is a rotatable shaft 13 which is pivoted through each end of the frame and carries two upstanding arms 14 and 15 at either end formed from any suitable material such as for instance steel plate. The shaft 13 is preferably positioned somewhat closer to one side of the frame 10 than the other so that the arms 14 and 15 can be moved to extend over the side of the frame with only a small degree of rotation of the shaft 13. A counterweight 16 is also carried by shaft 13 and is spaced therefrom by members 17 and 18. The relationship of the counterweight 16 to shaft 13 is preferably such that the counterweight exerts its maximum

rotational force when the arms 14 and 15 are extended over the nearest side of the frame 10 and urges the shaft 13 to rotate in such a manner that arms 14 and 15 are urged to become positioned with their upper extremities substantially centered with respect to the width of frame 10.

Detent means in the form of a pin 19 extending from the face of arm 14 and a catch 20 pivotally mounted on frame 10 are provided to retain the arms 14 and 15 extended over one side of the frame against the rotational force resulting from the counterweight 16. So that arms 14 and 15 will not be rotated through a greater arc than is desired when the catch 20 is released, arm 15 is provided with an extension 25 which is designed to contact a plate 26 welded to frame 10 when the upper extremities of arms 14 and 15 are substantially centered with respect to the width of frame 10.

The upper extremities of arms 14 and 15 are flared and are provided with convexly arcuate upper edges 27 and 28 which are adapted to enter the space at either end of a roll of material 29 adjacent the end faces 30 and 31 of the two heads 32 and 33 when the roll is properly positioned in the loom. There is generally ample room for even a thick member at the end of the roll adjacent the resiliently mounted pin since the flange pressing against the head of the roll is generally only slightly larger than the pin proper and the upper extremity of one arm of the truck can make contact with the end face without passing between the flange and the head of the roll. However, on the opposite end of the roll the flange on the driven pin is generally of larger diameter than the roll head and it is necessary that the upper extremity of the arm be quite thin so that it can be passed or forced between the flange and the end face of the head of the roll. For this reason it is frequently advantageous to bevel the edges 27 and 28 of arms 14 and 15.

Located slightly below the upper edges 27 and 28 on arms 14 and 15 are inwardly facing arcuate flanges 34 and 35 adapted to support the roll 29 by contact with the heads 32 and 33. The contour of flanges 34 and 35 is preferably such as to coincide with the curvature of the peripheral surfaces of the heads 32 and 33 of roll 29 and the width of members 34 and 35 should be such that they do not contact the woven material even when it is woven the full width of the loom. The flanges 34 and 35 should be so positioned with respect to arms 14 and 15 that when the arms are pivoted to extend over one side of the frame 10, the lowest point on the arcuate upper surface of each of the flanges is relatively near to the lower end thereof so that the flanges may be placed to allow a minimum drop of the roll 29 when it is released from the loom. The flanges 34 and 35 should also be so close to the upper ends of the arms 14 and 15 that the upper edges 27 and 28 do not contact the pins adapted to be inserted in the recesses 36 and 37.

In operation, the arms 14 and 15 are positioned to extend over the side of frame 10 and are locked into position by catch 20. The truck is then wheeled into the loom alley so that the arms extend toward the loom from which a roll of material is to be doffed. When the truck is properly positioned with respect to the loom, it is wheeled sideways toward the loom so that the upper edges 27 and 28 of arms 14 and 15 pass between the end faces of the two heads 32 and 33 of the roll 29 and the loom structure adjacent thereof and so that flanges 34 and 35 contact the peripheral surfaces of the heads 32 and 33. The truck is then pushed lengthwise in the direction of the resiliently mounted pin and because of the contact of the upper extremity of arm 14 or 15, depending upon which direction it is necessary for the truck to be moved, against the end face of one head of the roll of material, the roll of material is likewise moved in a lengthwise direction. When the roll has been moved lengthwise sufficiently for the driven pin to clear the roll, one end of the roll thereby becomes supported entirely by

flange 34 or 35 and that end of the truck can then be moved away from the loom a sufficient distance to allow the roll of material to be moved lengthwise in the opposite direction and thereby become free of the resiliently mounted pin. Catch 20 is then released and shaft 13 is rotated by means of counterweight 16 so that the roll of material becomes centrally positioned with respect to the width of the frame 10 as illustrated in Figure 2. The truck may then be wheeled through the loom alley to any desired point for the deposition of the roll of material.

Having thus described my invention what I claim and desire to secure by Letters Patent is:

- I claim:
15. A truck suitable for use in doffing a full roll of woven material from a loom, said truck comprising in combination a wheeled frame, a rotatable shaft carried by said frame, a pair of upstanding arms carried by said shaft, movable therewith and spaced from each other axially of said shaft, an amount substantially equal to the distance between opposite heads of a roll of woven material, means carried by the upper extremity of at least one of said arms for engaging the end face of one of the two heads of said roll when said truck is moved lengthwise whereby said roll is moved lengthwise and released from the loom, and means carried by said arms to support said roll by contact with the lower peripheral surfaces of the two heads thereof.
  20. A truck suitable for use in doffing a full roll of woven material from a loom, said truck comprising in combination a wheeled frame, a rotatable shaft carried by said frame, a pair of upstanding arms carried by said shaft, movable therewith and spaced from each other axially of said shaft, an amount substantially equal to the distance between opposite heads of a roll of woven material, each of said arms carrying an arcuate flange near the upper end thereof, said arcuate flanges being adapted to receive the two heads of said roll, and said arms having upwardly extending sections adapted to contact the ends of the two heads of said roll, whereby when the extremities of said arms are in peripheral and radial contact with the heads of a roll, lengthwise movement of the truck causes positive corresponding lengthwise movement of the roll.
  25. A truck suitable for use in doffing a full roll of woven material from a loom, said truck comprising in combination a wheeled rectangular frame adapted to be moved lengthwise between two rows of looms, a rotatable shaft positioned lengthwise of said frame, a pair of upstanding arms carried by said shaft, movable therewith and spaced from each other axially of said shaft, an amount substantially equal to the distance between opposite heads of a roll of woven material, each of said arms carrying an arcuate flange near the upper end thereof, said arcuate flanges being adapted to receive the two heads of said roll, means carried by the upper extremity of at least one of said arms for engaging the end face of one of the two heads of said roll when said truck is moved lengthwise with respect to said roll, and means urging said arms to become positioned with their upper extremities substantially centered with respect to the width of said frame.
  30. In a hand truck for doffing a full roll of woven material from a loom, the improvement which comprises a pair of substantially parallel upstanding arms having upper extremities of sufficient thinness to pass between the end face of the head of a roll of material supported by said loom and the section of the loom adjacent said end face, and an arcuate flange carried by each of said arms for supporting the ends of said roll by contact with the lower peripheral surfaces of the heads thereof.
  35. A truck suitable for use in doffing a full roll of woven material from a loom, said truck comprising in combination a wheeled rectangular frame adapted to be moved lengthwise between two rows of looms, a

rotatable shaft positioned lengthwise of said frame, a pair of upstanding arms carried by said shaft, movable therewith and spaced from each other axially of said shaft, an amount substantially equal to the distance between opposite heads of a roll of woven material, each of said arms having an upper extremity of sufficient thinness to pass between the end face of one head of a roll of material carried by the loom and the section of the loom adjacent said end face, said upper extremity having an upwardly facing edge of convex curvature, and inwardly facing arcuate flanges carried by each of said arms to contact the lower peripheral surfaces of the heads

of said roll when the upper extremities of said arms are inserted between the end faces of said heads and said loom.
